G. A. Watkins

UNITED STATES PATENT OFFICE.

G. A. WATKINS, OF SPRINGFIELD, VERMONT.

IMPROVEMENT IN HOOKS FOR FASTENING GARMENTS.

Specification forming part of Letters Patent No. 37,783, dated February 24, 1863.

To all whom it may concern :

Be it known that I, G. A. WATKINS, of Springfield, in the county of Windsor and State of Vermont, have invented a new and improved hook-fastening for india-rubber blankets and other garments designed for military or army purposes; and I do hereby declare that the following is a full, clear, and exact description of the same, reference being had to the accompanying drawings, making a part of this specification, in which—

Figure 1 is a side view of my invention; Fig. 2, a transverse section of the same, taken in line x x , Fig. 1; Fig. 3, a perspective view of the same; Fig. 4 a side view of a modification of the same; Fig. 5, a transverse section of the same, taken in the line y y , Fig. 4; Fig. 6, a perspective view of the same.

Similar letters of reference indicate corresponding parts in the several figures.

This invention consists in attaching a hook to the blanket or garment by means of an eyelet in the manner herein shown and described.

To enable those skilled in the art to fully understand and construct my invention, I will proceed to describe it.

A represents a hook, which may be constructed of brass or other suitable metal, and of any proper or desirable form. The end of the shank a of the hook is flattened, and is so swaged or formed as to have a tubular projection, b , projecting at right angles from about the center of the flattened portion, as

shown clearly in Fig. 3. The opening of the projection b extends entirely through the shank a , and the shank a , with the tubular projection b , forms an eyelet, as shown in Fig. 3.

When this device is to be attached to a blanket or garment provided with eyelets c , no burr or washer is required, as the eyelet in the garment answers the purpose of a washer, as shown in Fig. 2, the projection b being passed through the eyelet c . If the garment is not provided with the eyelets c , the projection b is simply passed through a hole in the garment, and a burr or washer, d , as shown in Fig. 3, is employed, over which the end of the projection b is bent or swaged. By this mode of attaching the hook to the blanket or garment the former is allowed to swing or turn in the latter, so that the hook may be readily adjusted in the blanket or garment to secure the same on the wearer.

Having thus described my invention, what I claim as new, and desire to secure by Letters Patent, is—

A fastening for india-rubber and other blankets and garments, designed for military or army use, composed of a hook and an eyelet, attached permanently to the shank a , substantially as herein shown and described.

G. A. WATKINS.
